(57) **CLAIM**

The ornamental design for a plastic film with surface pattern, as shown and described.

DESCRIPTION

FIG. 1 is a top plan view of a first embodiment of a plastic film with surface pattern showing our new design; and, FIG. 2 is a top plan view of a second embodiment of a plastic film with surface pattern showing our new design.

The dash-dot-dash broken lines shown along the border of the plastic film with surface pattern depict the boundaries of the claimed design and form no part thereof.
